UNITED STATES PATENT OFFICE.

SETH MULVANEY, OF INGLEWOOD, CALIFORNIA, ASSIGNOR OF ONE-HALF TO
FREDERICK K. HURXTHAL, OF LOS ANGELES, CALIFORNIA.

HEATER FOR GASEOUS FUEL.

1,128,998.

Specification of Letters Patent. Patented Feb. 16, 1915.

Application filed November 17, 1913. Serial No. 801,417.

To all whom it may concern:

Be it known that I, SETH MULVANEY, a citizen of the United States, residing at Inglewood, California, have invented a new and useful Heater for Gaseous Fuel, of which the following is a specification.

This invention relates to a charge forming device to break up more thoroughly the liquid fuel, and at the same time heat it sufficiently to vaporize the heavier oils such as distillate.

In carrying out this invention there is provided a compact, inexpensive device that can be readily attached to internal combustion engines now on the market, and which is adapted to utilize the heated blast from the exhaust to heat in an efficient manner the spray of liquid fuel. This device provides a large heat-radiating area in comparison to its compact and simple construction. The entire fuel fed to the engine may be made to take a course that brings it into immediate contact with said heat-radiating area.

25 The invention comprises an improved heat-radiating device and also improved means to conduct heated gas from the exhaust to said device to heat the same.

Referring to the accompanying drawings, 30 which illustrate the invention,—Figure 1 is an elevational view of a portion of an internal combustion engine, its carbureter and fuel pipes being shown, and the device which forms the subject matter of this invention being shown connected therewith, said device being sectioned. Fig. 2 is an enlarged side elevation of the heater, part of the casing being broken away. Fig. 3 is an edge view of the heater, partly in section. 35 Fig. 4 is an enlarged detail view of the means for catching the exhaust gas.

Referring in detail to the drawings, the main fuel supply pipe is formed in two sections 5 and 6 between which is inserted a 45 casing 7 that contains a charge heating and vaporizing body 8. Said body 8 is heated by passing therethrough a portion of the exhaust gases from the manifold pipe 9 of the engine 11. To this end a supplemental 50 exhaust pipe 12 is provided at one end with a goose-neck 13, the end portion of which is tapped into the exhaust pipe 9 and has within said pipe 9 a lateral inlet opening 14 directed toward the exhaust. The other end 55 of pipe 12 is led through the edge of casing

7, (see Fig. 3), and discharges into the hollow heat-radiating body or drum 8 which is preferably made of copper and furnished with heat-radiating and fluid-retaining ribs 15. The other side of body 8 (opposite pipe 12) is provided with an outlet pipe 16. Hence a considerable portion of the heated exhaust passes continuously through the drum 8. The sides of the drum 8 extend into the casing 7 beyond the edge of the intake opening formed by the pipe 5, with the result that the incoming fuel is deflected outwardly from said intake and is compelled to pass into close proximity to the heating drum 8. The liquid fuel, being heavier than the atmosphere, will all be thrown against the end of said heating drum, to be retained between the ribs 15 until vaporized.

The pipe 12 which conveys the heated gas to the charge forming device proper is 75 formed in two sections, 12^a and 12^b which are united by screw-threaded coupling member 17, as shown in Fig. 1. Said coupling member 17 cooperates with the gooseneck portion 13 of the pipe 12 to provide a device that can be very readily connected up with automobile engines now on the market. The gooseneck arrangement permits the hole for receiving the pipe 12 to be tapped 80 through the side of the manifold pipe 9 opposite the charge forming device 7. The gooseneck 7 can be rotated to bring the open end thereof into position for insertion into manifold pipes considerably lateral to pipe 12, thereby adapting the heater for 85 ready application to engines differing in design. Then after the extreme end portion of the pipe 12 has been inserted through the wall of the pipe 9 the section 12^a of the pipe 12 is readily drawn toward the section 12^b 90 of said pipe in the act of coupling said sections together.

21 designates a carbureter of well known make having a distillate feed pipe 22 and needle valve 23 from which the suction of 100 the engine draws in the distillate in the form of partly vaporized spray and throws it forcibly against the ribbed portion 15 of the drum 8 thereby in an efficient manner vaporizing and heating the distillate or other 105 heavy liquid fuel used.

Pipe 5 is provided with a throttle valve 24.

A gasoline feeding device for use in starting is illustrated in Fig. 1. From the gasoline tank 31 a conduit 32 leads to the spray- 110

ing chamber 33 which communicates with the supply pipe 6 between the casing 7 and intake manifold pipe 34.

35 is a hand wheel to control the gasoline feed.

I claim:—

1. In a heater for gaseous fuel a heater provided with an inlet and an outlet, a hollow body within said casing, said body being of the shape of a drum having relatively flat portions, and a conduit to conduct heated gas from the discharge of an engine into said casing and through said drum to heat the latter, one of the flat portions of said drum being directed toward said inlet and being provided with ribs to retain the liquid portion of the fuel, there being an annular space around said drum between the same and the inner wall of said casing.
2. In a heater for gaseous fuel, a charge forming element proper, and a heating pipe to conduct heated gas from the discharge

manifold pipe of an engine to the interior of said heating element to heat a portion thereof, said heating pipe consisting of two sections united together by a coupling, the intake end of said heating pipe comprising a laterally adjustable gooseneck the tip portion of which is tapped into the side of said manifold pipe opposite the charge forming device proper, there being a lateral opening in the end portion of said heating pipe within the manifold pipe, said opening being directed toward the exhaust which passes through the manifold pipe.

In testimony whereof I have hereunto signed my name in the presence of two subscribing witnesses at Los Angeles, in the county of Los Angeles and State of California, this 8th day of November, 1913.

SETH MULVANEY.
